UNITED STATES PATENT OFFICE.

LETTIE VALIRIA NORTHRUP, OF FORT COBB, OKLAHOMA.

THERMOMETER-HOLDER.

1,357,893.

Specification of Letters Patent.

Patented Nov. 2, 1920.

Application filed June 7, 1920. Serial No. 387,084.

To all whom it may concern:

Be it known that I, LETTIE VALIRIA NORTHRUP, a citizen of the United States, residing at Fort Cobb, in the county of Caddo and State of Oklahoma, have invented certain new and useful Improvements in Thermometer-Holders, of which the following is a specification.

This invention relates to thermometer holders for incubators.

The object of the invention is to provide a simple and efficient device of this character which will reliably yet detachably support a thermometer bulb in contact with an egg without displacing the eggs and which cannot be overturned by the chicks when hatching takes place.

Another object is to so construct such a holder which after being mounted on the screen which supports the egg tray may remain there throughout the period of incubation and which is equipped with means for detachably supporting a thermometer so that the thermometer may be easily applied and removed without disturbing the eggs.

With these and other objects in view, the invention consists in certain novel features of construction as hereinafter shown and described and then specifically pointed out in the claims, and in the drawings illustrative of the preferred embodiment of the invention.

In the accompanying drawings:

Figure 1 represents a side elevation of this improved holder shown applied with the incubator screen and egg tray in section.

Fig. 2 is a rear elevation thereof.

Fig. 3 is a transverse vertical section taken on the line 3—3 of Fig. 1.

Fig. 4 is a top plan view of a portion of an incubator screen with this improved attachment shown applied, and,

Fig. 5 is a perspective view of the attachment detached and having the thermometer shown mounted therein in dotted lines.

In the embodiment illustrated an incubator screen of ordinary construction is shown at S with an egg tray T mounted thereon. The thermometer holder 1 constituting this invention is shown applied to the screen S and is composed of sheet metal preferably of aluminum and is struck out from a single piece of metal comprising a standard 2 having a foot 3 projecting at right angles from its lower end and having on its side edges laterally extending grip-

ping fingers 4 equipped with downturned terminals 5 which are designed to be passed through the meshes of the screen S and clamped thereunder as is shown clearly in Figs. 1 and 4.

The standard 2 has its upper end extended outwardly and upwardly to form an inclined arm 6 which is folded inwardly upon itself at 7 the overlying portion 8 being provided with upstanding struckout spring gripping fingers 9. These fingers 9 are arranged in staggered relation and are designed to receive between them the thermometer t which may be of any ordinary construction such as is employed in connection with incubators.

This improved holder is designed to be mounted at one side of the egg tray T so that the tray may be removed when desired without interfering with the holder and which also provides for the positioning of the thermometer between two eggs with its bulb B in contact with one of the eggs which is necessary to obtain the best results enabling the operator to determine the exact temperature of the eggs.

From the above description it will be obvious that this holder 1 when mounted on the screen S by clamping the fingers 4 thereof around and under the screen wires will be reliably held against all possibility of its being overturned by the chicks when hatching and yet will permit the thermometer to be removed and applied at the will of the operator without in any way interfering with the eggs.

The preferred embodiment of the invention is disclosed in the drawings and set forth in the specification, but it will be understood that any modifications within the scope of the claims may be made in the construction without departing from the principle of the invention or sacrificing any of its advantages.

What is claimed is:

1. A device of the class described comprising a support engaging base with a standard arising therefrom and having an upwardly and outwardly inclined arm at its upper end provided with a folded downturned portion having spring fingers to support a thermometer.

2. A device of the class described comprising a standard having means at one end to secure it to a support, and an upwardly and outwardly inclined laterally extending arm

at its other end provided with upstanding laterally and longitudinally spaced staggered spring fingers to receive and support a thermometer.

5 3. A device of the class described comprising a unitary structure struck from a single piece of sheet metal, and including a standard having its lower end bent laterally at right angles to form a support engaging foot

equipped with downturned fingers on its 10 side edges, the upper end of said standard being bent laterally outward and upward and folded inwardly upon itself, the overlying portion being equipped with outstruck upstanding spring fingers.

In testimony whereof, I affix my signature hereto.

LETTIE VALIRIA NORTHRUP.
